COUPLER PIN PROTECTOR

Frank H. Kayler, Alliance, Ohio, assignor to
 American Steel Foundries, Chicago, Ill., a corporation of New Jersey

Application August 6, 1949, Serial No. 108,877

7 Claims. (Cl. 213—155)

1

This invention relates to railway couplers and more particularly to the type in which a knuckle is rotatably connected to a coupler head by a pin and wherein means are provided to protect the pin against wear and to relieve the pin from draft and buffing stresses when the coupler is in service.

In present couplers these means comprise bosses on the coupler head surrounding the pin and shoulders on the knuckle extending partially around the bosses for abutment therewith. The mating surfaces on the bosses and the shoulders are not machined and are afforded clearance therebetween as established by manufacturing tolerances to insure that the parts will fit. In order to permit movement of the knuckle to engage the shoulders thereon with the bosses without subjecting the pin to great shearing stresses, the pin holes in the bosses and knuckle are made larger than the pin. The construction thus far described is well known in the art and provides, in effect, a floating pin arrangement, the pin serving as a pivot for the knuckle when it is being opened and to retain the knuckle against displacement.

Due to the conditions under which A. A. R. Standard couplers operate in service, it is highly desirable that the operations of unlocking coupler and opening knuckle by means of the conventional operating rod be made as easy as possible to counteract the temptation for an operator to step between the cars to open the knuckle directly by hand, which it will be understood is a dangerous practice.

It is, therefore, desirable to reduce frictional resistance to free operation of the knuckle to a minimum while still retaining all desirable features of operation and service wear resistance of this design.

I have discovered one cause of considerable frictional resistance to free knuckle opening to be due to contact and wedging action between portions of pin protector surfaces on the knuckle and the coupler body, and that this can be eliminated by a change in construction, explained as follows:

The large pin holes in body of this type coupler permit movement of the pin and the knuckle into such a position by the operating mechanism during knuckle throwing or opening operation that the mating surfaces of the bosses and shoulders are positioned eccentrically and that certain of these surfaces are caused to engage tangentially, thereby producing a wedging action between the shoulders and the bosses and fric-

2

tionally resisting opening of the knuckle. To open the knuckle, this arrangement necessitates shifting of the knuckle laterally of the coupler and overcoming the frictional resistance between the normally unfinished surfaces on the knuckle and the boss supporting the knuckle.

A general object of the invention is to provide a simple means efficiently operating to relieve the pivot pin from pulling and buffing stresses and accommodating free opening of the knuckle by the operating mechanism irrespective of the position of the knuckle.

A more specific object is to modify the construction of the bosses in such manner that binding or wedging action with the shoulders during opening of the knuckle is prevented.

A further object is to provide an arrangement wherein surface contact areas between the bosses and the shoulders remain the same as in present arrangements and wherein certain surface portions of the bosses around which the shoulders pass when the knuckle is rotated to open position are of novel configuration to afford clearance for the shoulders when the knuckle is rotated to open position.

The invention particularly contemplates an arrangement to be used with present knuckles.

Another object is to provide an inexpensive arrangement which will overcome the difficulties mentioned and have long life in service.

These and other objects will become more apparent from the specification and the drawings, wherein:

Figure 1 is a fragmentary side elevational view of a coupler incorporating the invention, the view being taken from the knuckle side of the coupler;

Figure 2 is a fragmentary sectional view taken substantially on the line 2—2 of Figure 1, and showing the knuckle closed in top plan and the knuckle thrower in phantom lines; and

Figures 3 to 5 are fragmentary enlarged views of the structure shown in Figure 2, Figure 3 showing the position of the parts with the knuckle closed, Figure 4 showing the position of the knuckle moved by the operating mechanism prior to rotation, and Figure 5 showing the knuckle rotated to open position.

Referring to the drawings in detail, the coupler comprises a head 2 with spaced top and bottom lugs or ears 4, 4 provided with bosses 6, 6 on their adjacent sides. A knuckle 12 is pivoted to the head by a pin or bolt 14 extending through vertically aligned openings 16, 16 in the bosses and ears and opening 18 in the body portion 20 of the knuckle fitted between bosses 6, 6 and

slidably supported as at 22 on the bottom boss 6. The coupler head is preferably formed as a casting and the openings 16 are made larger than the pin, the openings 16 being preferably oval-shaped and elongated longitudinally of the coupler. The opening 18 for purpose of illustration is shown the same diameter as the pin.

Each boss 6 is generally round in cross section and formed at the juncture of its outboard and inner sides rearwardly of the pin with a stop member 24 formed integral with the associated lug 4 and a side wall 26 (Figure 1) of the head, said stop member presenting a generally vertical abutment face 28 extending longitudinally of the coupler and disposed rearwardly of the associated boss 6. Each stop member also presents a generally vertical abutment face 30 disposed outboard of the associated boss and extending transversely of the coupler and facing forwardly thereof.

Each boss 6 is provided with generally vertical substantially cylindrical convex draft and buff abutment surfaces 32 and 34 aligned longitudinally of the coupler and disposed, respectively, rearwardly and forwardly of the pin on the inner and outer sides of the boss. The inner surface extends between face 28 on stop member 24 and a substantially vertical flat surface 36 on the inboard side of the boss, said surface 36 extending between surfaces 32 and 34.

Each boss is partially loosely surrounded by a U-shaped shoulder, generally indicated 38, and formed integral with the body portion of the knuckle, said shoulder comprising inner and outer legs 40 and 42 joined by an intermediate portion 44 at the inboard side of the associated boss. It will be understood that a shoulder 38 is formed on the top and on the bottom of the body portion of the knuckle as seen in Figure 1.

The legs 40 and 42 are provided on their internal sides with generally vertical concave draft and buffing surfaces 46 and 48 complementary to surfaces 32 and 34, respectively, for abutment therewith when the knuckle is closed and shifted longitudinally of the coupler under draft and buffing forces in service as accommodated by the enlarged oval-shaped openings 16, 16. The inner side of the intermediate portion 44 of each shoulder is provided with a substantially flat vertical surface 50 extending between surfaces 46 and 48. It will be noted that by flattening surfaces 36 and 50, substantial thickness is afforded through portion 44 of each shoulder as seen in Figure 2.

Considering now Figures 2 and 3, it will be noted that the knuckle is in closed position preparatory to its opening by the knuckle thrower or opener 52 of a conventional operating mechanism well known in the art, the thrower 52 engaging a bearing pad 54 on the knuckle rearwardly of the pin 14. In this position of the knuckle, the legs 40 and 42 of the shoulders are disposed rearwardly and forwardly, respectively, of the related bosses and the surfaces 32, 34, 46 and 48 are aligned longitudinally of the coupler. The free end of leg 40 of each shoulder presents a generally vertical face 56 adjacent face 28 on stop lug 24 adapted for abutment therewith to limit counterclockwise rotation of the knuckle. The free end of leg 42 of each shoulder terminates in a flat, generally vertical face 58 spaced from face 30 on the stop 24 and adapted for abutment therewith to limit clockwise rotation of the knuckle to open position as shown in Figure 5.

It will be understood that during opening of the knuckle the legs 42 will pass around the out-

board sides of the bosses and that in the closed position of the knuckle the free ends of legs 42 are spaced from stops 30 on member 26.

In opening the knuckle, the thrower 52 initially shifts or moves the knuckle transversely of the coupler to the right, as shown in Figure 4, until the pin engages the inboard side of each pin hole 16 as at 60 (Figures 4 and 5) and until the knuckle engages the pin if the pin hole 18 in the knuckle is larger than the pin. As readily seen in Figure 4, the surfaces 46 and 48 are shifted to a position eccentric with respect to surfaces 32 and 34 on the bosses, and each surface 48 engages the associated surface 34 at a point 62 adjacent face 58 on the associated leg 42, said point 62 being disposed in a vertical plane extending longitudinally of the coupler outboard of the axis 64 of the pin in the closed position of the knuckle and the path of movement of point 62 is along the arc indicated at 66 when the knuckle is rotated to open position. In order to accommodate unrestricted rotation of the knuckle, point 62 is prevented from engaging the outboard side of the boss by forming the outboard side of each boss with a depression or recess 68 defined by a surface 70 disposed inwardly of arc 66, or in other words the radius of surface 70 is less than the radius from axis 64 to arc 66. Each surface 70 extends at one end to face 30 on member 24 and at the other end flares outwardly and merges with surface 34 adjacent the forward or outer side of the boss.

The novel arrangement has been found in actual practice to accommodate free rotation of the knuckle to open position by the operating mechanism. Wedging action between the knuckle shoulders and the bosses and consequent lateral shifting of the knuckle during rotation to open position is entirely eliminated as a consequence of which substantially less force is required to actuate the operating mechanism and open the knuckle. The novel configuration of the bosses, while improving the operation of the knuckle, affords maximum bearing area for the shoulders of the knuckle and requires no change in the knuckles presently in use.

I claim:

1. In a coupler, a coupler head comprising spaced top and bottom ears with bosses on their adjacent sides, a knuckle extending between said bosses and loosely rotatably connected thereto on an axis accommodating shifting of the knuckle laterally and longitudinally of said coupler, U-shaped shoulders on the top and bottom of said knuckle loosely partially surrounding respective bosses, each shoulder comprising inner and outer legs and an intermediate portion interconnecting the legs, said inner and outer legs and said portion being disposed along the inner and outer and inboard sides, respectively, of the associated boss in the closed position of said knuckle, each boss being provided with convex surfaces on its inner and outer sides and a substantially flat surface on its inboard sides extending between and merging with the adjacent convex surfaces, each shoulder being provided with concave surfaces on its inner and outer legs adapted to be positioned in concentric relationship with the convex surfaces on said bosses when said knuckle is in closed position, each portion having a substantially flat surface adapted to lie along the flat surface on the related boss in the closed position of said knuckle, said bosses having their outboard sides offset and spaced inboard of the path of movement of said surfaces on said outer

legs during rotation of said knuckle when said knuckle is shifted a maximum amount laterally of said coupler in a direction inboard of said bosses.

2. In a coupler, a coupler head comprising vertically spaced top and bottom lugs with bosses on adjacent sides thereof, a knuckle extending between said bosses and pivotally connected thereto on a shiftable axis accommodating rotational, lateral and longitudinal movement of said knuckle with respect to said head, said knuckle comprising U-shaped shoulders on the top and bottom thereof loosely, partially surrounding respective bosses, each shoulder comprising inner and outer legs and an intermediate portion interconnecting the legs, said inner and outer legs and portion being disposed in the closed position of said knuckle along the inner, outer and inboard sides of the associated boss, respectively, said legs and inner and outer sides of said bosses being provided with mating surfaces disposed in concentric relationship in the closed position of the knuckle, means for operating said knuckle comprising a thrower adapted to initially shift said knuckle in a direction inboard of said bosses and then rotate said knuckle to open position on an axis spaced inboard with respect to that of said surfaces on the bosses, said bosses having their outboard sides offset and spaced inboard of the path of movement of said surfaces on said outer legs of said shoulders during rotation of said knuckle on said last-mentioned axis.

3. A car coupler described in its normal closed position, comprising a coupler head having spaced ears and a knuckle therebetween, a pin extending through aligned openings in said ears and knuckle, cooperating draft and buffing faces on said knuckle and ears disposed forwardly and rearwardly of said pin, respectively, said knuckle faces fitting loosely around the faces on said ears and said openings being larger than the diameter of the pin to accommodate movement of said knuckle longitudinally of said coupler under buff and draft stresses to engage said faces on said knuckle with those on said ears without imposing shearing stresses on said pin, means for rotating said knuckle to open position and engageable therewith rearwardly of said pin, said knuckle being movable laterally with respect to said coupler in a direction inboard of said ears until said knuckle engages said pin and said pin engages said ears under the action of said means, said buffing faces being terminated adjacent the outboard side of said ears, the outboard sides of said ears being formed with depressions extending from said buffing faces thereon to the juncture of said ears with said head whereby the buffing faces on the knuckle are in spaced relation to the outboard sides of said ears during movement of the knuckle to its open position.

4. In combination with a coupler head, of a knuckle rotatable with respect to the head and shiftable laterally and longitudinally thereof, mating bearing surfaces on said head and said knuckle forward and rearward of the axis of ro-

tation of said knuckle and adapted to be positioned in concentric relationship and aligned longitudinally of said head in the closed position of said knuckle, means for rotating said knuckle to open position including a thrower engageable with the knuckle rearward of said axis, said thrower initially shifting said knuckle transversely of the coupler head, whereby said surfaces on the knuckle are shifted to a position eccentric with respect to the surfaces on said head, said surfaces on said head forward of said axis merging with faces on said head around which the surfaces on the knuckle forward of said axis are adapted to pass during rotation of said knuckle from closed to open position, said faces being disposed closer to the axis of rotation of said knuckle than said last-mentioned surfaces whereby the knuckle is free to move to its open position without frictionally engaging said faces.

5. In a railway coupler, a coupler head comprising spaced lugs with bosses thereon, a knuckle between said bosses, a pin extending loosely through aligned openings in said lugs, bosses, and knuckle, shoulders on said knuckle loosely partially surrounding said bosses and having faces engageable with complementary concentric faces on said bosses during buffing and pulling action in the closed position of said knuckle, the portions of said bosses not surrounded by said shoulders in the close position of said knuckle and adapted to be passed by said shoulders during opening of the knuckle having external surfaces offset from their adjacent concentric faces toward the axis of rotation of said knuckle whereby the knuckle is free to move to its open position without contacting said surfaces.

6. A coupler head comprising spaced portions aligned substantially vertically and provided with generally vertical aligned openings therethrough, external convex surfaces on the forward sides of the portions defined from the central axis of said openings, each portion comprising an external face on its outboard side contiguous to said surfaces and defined from said axis and of lesser radius than said surfaces.

7. A coupler head comprising spaced vertically aligned top and bottom ears, a boss on the bottom side of said top ear, a boss on the top side of said bottom ear, and convex, generally vertical draft and buffing surfaces on the forward and rear sides of each boss, respectively, said bosses having their outboard sides offset inwardly of the projection of the buffing surfaces on said forward sides.
